UNITED STATES PATENT OFFICE.

JUNIUS A. BRAND, OF NORWICH, CONNECTICUT.

FUSE FOR EXPLOSIVE PROJECTILES.

SPECIFICATION forming part of Letters Patent No. 223,312, dated January 6, 1880.

Application filed October 27, 1879.

To all whom it may concern:

Be it known that I, JUNIUS A. BRAND, of 5
Norwich, in the county of New London and
State of Connecticut, have invented a new and
useful Improvement in Fuse-Igniters for Ex-
plosive Projectiles; and I do hereby declare
the same to be described in the following spec-
ification, and represented in the accompanying
drawings, of which—

10 Figure 1 is a side view, Fig. 2 a longitudi-
nal section, and Fig. 3 an end view, of a fuse-
tube or bomb-lance shank provided with my
invention, which relates to the screw-cap of
the said tube or shank, and to the firing-pin
15 and the percussion-cap holder thereof, and is
not only to seal the firing-pin chamber and
hold the firing-pin in position so as to prevent
it from being accidentally driven against the
cap, but is to prevent the latter, when back
20 upon the end of the firing-pin chamber, from
sealing such end so as to prevent or materially
obstruct the escape of the gases incident to the
combustion of the charge of the primer and
fuse.

25 Fig. 4 is a top view, and Fig. 5 a transverse
section, of the firing-cap holder A. This holder
is a flanged cup having a vent-hole, a, through
the center of its bottom, and also two other
vent-holes, b b, through its flange c. The per-
30 cussion powder or composition is placed within
in a small cup or cap, d, which is inserted and
fitted closely into the recess of the holder.
The said percussion-cap-priming holder has a
diameter equal, or about equal, to that of
35 the fuse-tube carrier B, which, in this case, is
to be supposed to be the tubular shank of an
explosive bomb-lance, such as is used in cap-
turing or killing whales or various other sea-
animals. A fuse, C, properly supported with-
40 in the carrier B, terminates at one end near
the cap-holder A, which is held in place by a
metallic cap, D, which is screwed upon the
carrier B and against the flange of the holder.
Directly in front of the holder there is, with-
45 in the said cap D, a shallow circular recess or
chamber, e, which communicates with the fir-
ing-pin chamber f by a passage, g, having a
diameter a little greater than that of the shank
h of the firing-pin E. In the bottom of the
50 chamber e are one or more grooves or chan-

nels, i, leading into the firing-pin-shank pas-
sage g.

Fig. 6 is a rear view of the cap D, showing
two of the said channels i, which are formed
by a groove extending diametrically in and 55
across the bottom of the chamber e.

The firing-pin E has a cylindrical head, k,
which is provided at its outer end with a thin
yielding flange, l, that fits into a shallow cham-
ber or recess, m, made in the cap D at the outer 60
end of the firing-pin chamber. The said flange
l is to be strong enough to support the firing-
pin in place, so as to prevent it from being ac-
cidentally thrown forward against the percu-
sion-cap or primer. The said flange, however, 65
should be incapable of withstanding the force
of the explosion of the charge of the gun from
which the missile or projectile may be dis-
charged. The flange, by means of cement or
a suitable sealing material, is to be hermeti- 70

75 On explosion of the charge of the gun taking
place, the firing-pin, by the force thereof, will
be broken away from the flange and driven
forward against the primer or percussion-cap,
so as to cause the fulminate or composition 80
thereof to be exploded. On firing of the ful-
minate or charge of the primer or cap d so tak-
ing place, the said cap is liable to be driven
channel or channels i in the bottom of the 85
back with great force; and, were it not for the
chamber e, such cap, on being so driven back,
would be liable to stop the firing-pin-shank
passage g, and thus prevent escape of the
smoke and gas produced. So, were it not for 90
the shallow chamber e, its channel or channels
i, and the vent hole or holes of the percus-
sion-cap holder, the escape of gas from combus-
tion of the fuse might be interrupted or prevented
by the percussion-cap when covering the pas- 95

95 Should the hole in the bottom of the cap-
holder become obstructed, or the cap not be
forced back out of it, the vent hole or holes in
the flange of the holder will allow escape of
the gases into the chamber e, from whence such
gas or gases will be discharged through the 100
firing-pin chamber.

Previous to my present invention I have
made the firing-pin-chamber sealing-disk sepa-

rate from the firing-pin, and applied to the latter a spring to force or hold it back against the disk, in order to prevent such pin from being accidentally driven forward. My present improvement enables me to dispense with such spring, which I accomplish by providing the firing-pin with the yielding sealing-flange, directly attached to or in one piece with it, the said pin.

10. What, therefore, I claim as my invention is as follows:

1. The cap D, provided with the chamber f, the annular sealing-recess e, and the firing-pin, arranged as set forth and having a yielding sealing-flange, m, extending from and connected with the said pin, and hermetically sealed in the said recess e, all being substantially as explained, whereby the said flange is made not only to support the firing-pin, but to 20 serve as a means of hermetically estopping the

outer end of the chamber in which such pin is arranged.

2. The shank-cap D, provided with the shallow chamber e and one or more channels, i, arranged therewith and with the firing-pin chamber substantially in manner and for the purpose specified, in combination with the cap-holder A and the percussion-cap thereof, arranged as set forth. 25

3. The holder A, provided with the bottom and flange vents, a b, and the cap d, as explained, in combination with tube B and with the firing-pin and its supporting-cap D, having the shallow chamber e and one or more channels, i, arranged, with the firing-pin chamber, substantially as represented. 30

JUNIUS A. BRAND.
